UNITED STATES PATENT OFFICE.

FREDERICK A. WAGNER, OF NORWOOD, OHIO.

COMBINED DRILL, CENTER-REAMER, AND COUNTERSINK TOOL.

1,017,352.

Specification of Letters Patent. Patented Feb. 13, 1912.

Application filed May 16, 1910, Serial No. 561,537. Renewed December 21, 1911. Serial No. 667,214.

To all whom it may concern:

Be it known that I, FREDERICK A. WAGNER, a citizen of the United States, residing at Norwood, in the county of Hamilton and 5 State of Ohio, have invented certain new and useful Improvements in Combined Drill, Center-Reamer, and Countersink Tools, of which the following is a specification.

10 My invention has for its object the providing of a tool combining a drill, center reamer and countersink, in which the cutting edges are located on a separate blade of high speed steel insertible and secured in 15 place in a head in novel manner, and the invention will be readily understood from the following description and claims, and from the drawing, in which latter:

Figure 1 is a side elevation of my improved device. Fig. 2 is an edge elevation of the same. Fig. 3 is an end elevation of the same. Fig. 4 is an axial section of the same taken on the line $z-z$ of Fig. 1. Fig. 5 is a perspective view of the blade in separated relation. Fig. 6 is a perspective view of the head in separated relation. Fig. 7 is a cross-section on the line $y-y$ of Fig. 1. Fig. 8 is a cross-section on the line $x-x$ of Fig. 1. Fig. 9 is a longitudinal section on the line $w-w$ of Fig. 1; and, Fig. 10 is a side elevation of a shaft partly broken away, having its end shown in central axial section, for exposing the hole formed by my improved device.

35 1 is a head which is provided with a longitudinal slot 2 extending across the longitudinal axis of the head. The head is preferably composed of ordinary steel, such as machinery steel or cold rolled steel, and is 40 a comparatively soft steel.

3 is a flat cutter-blade and comprises a drilling section 3^a , a center-reaming section 3^b , and a countersinking section 3^c , each of which is provided with cutting edges, the 45 cutting edges at the respective edges of said flat cutter-blade merging into each other, and together form a combination drilling, center-reaming and counter-sinking blade. The blade is a flat blade and is received in 50 the longitudinal slot 2, preferably with its inner end against the bottom of the slot for shouldering the inner end of the blade against said bottom. The blade is provided with apertures 4 and 5 through which the 55 clamp-screws 6 and 7 are respectively re-

ceived and in which said clamp-screws have a snug fit for locating said drilling, center-reaming and countersinking blade laterally and in central line with the longitudinal or rotary axis of the head.

The longitudinal slot in the head, which extends through the outer end of the head, forms the head into two mating clamping-wings 8 and 9 between which the combined drilling, center-reaming and counter-sinking blade is received and clamped by the clamp-screws 6 and 7. The clamp-screws are received through the bores 10 in one of said wings and threaded into internally threaded bores 11 in the other of said wings, 70 the heads 12 of said screws being received in enlarged bores 13 in the wings 8, between which and the bores 10 shoulders 14 are located, against which the heads of the screws exert pressure for pressing the wings toward each other.

The drilling section 3^a of the blade is provided at the respective sides of its median line and at opposite sides of the blade with end cutting-edges 15 and side cutting-edges 16, these side cutting-edges being preferably parallel.

At the center-reaming section 3^b the blade is provided at the respective sides of its median line and at opposite sides of the blade 85 with inclined center-reaming cutting-edges 17 which connect with the side cutting-edges 16 and respectively extend from said respective side-cutting edges at obtuse angles, the said tapering cutting-edges being however 90 at an acute angle with relation to each other. The counter-sinking section 3^c of the cutter-blade is provided with end cutting edges 18 at the respective sides of its median line and at opposite sides of the blade, which are 95 substantially perpendicular to the rotary axis of the cutter-head but recede slightly rearwardly from said perpendicular line and merge into said inclined center-reaming cutting-edges at an obtuse angle thereto, and in turn merge into inclined cutting edges 19 which recede outwardly from said end cutting-edges 18, preferably at an obtuse angle thereto, these last-named cutting edges being at the respective sides of the 100 median line of the blade and at opposite sides of the blade. These cutting edges are arranged in pairs respectively located at the lateral edges of the cutter-blade for forming a flat cutter-blade which has a pyrami- 105 110

dally formed middle reaming-section merging into a drilling section at its outer end and a counter-sinking section at its inner end so that when the tool is used it will form 5 a hole having an inner drilled portion 20, a middle annular tapered wall 21 which is distanced from the end 22 of the piece 23 operated on, shown as a shaft, by the countersunk portion 24 of the hole, which is 10 formed at one operation by my improved device. By these means a center-ream, is provided in the end of the piece operated on, instanced as a shaft, which has a clearance drill at the inner end of its tapered wall, 15 and the outer end of the tapered wall of which is distanced from the end of the shaft and counter-sunk therein so as to protect the same against contact with other bodies for preventing nicking or chipping of said 20 center-ream and preserving said center-ream in perfect condition for enabling the same to be used repeatedly without refinishing, the various sections of the hole being formed at one operation for insuring accuracy in an 25 economical manner.

The respective edges of the blade at their cutting-edge portions are provided with clearance rakes 31 32 shown in the form of grooves extending longitudinally of said cutting-edges and following the angles thereof in the respective side faces of said blade and extending inwardly from said cutting edges toward the rotary axis of the head. The outer edges of said blade in rear of 35 said cutting edges are provided with relieving rakes 33 34 which also extend lengthwise of said cutting edges and follow the angles thereof.

The wings are respectively provided with 40 parti-conical ends 35 36 which are received at the respective sides of the median tapered center-reaming portion 3^b of the cutter-blade and project toward the drilling section 3^a of said blade and terminate at their outer 45 ends adjacent the meeting line between said drilling section and center-reaming section, and have shoulders 37 38 at their inner ends adjacent the end cutting-faces 18. The said wings are further provided with parti- 50 conical portions 39 40 between said last-named shoulders and the outer walls of said wings. The parts are so formed that the said cutter-blade at its cutting edges extends but slightly beyond the portions of 55 the head just mentioned for imparting maximum strength to the head and maximum support against the cutting action to the blade. One of the side edges of each of the wings adjacent the cutting edge of 60 the blade at said side is provided with a recess 41, the wall of which describes a circle which intersects the said cutting edge adjacent its outer end, and the wall of said recess adjacent said blade describes a curve 65 on a smaller circle than the curve described

by the end of said recess adjacent that portion of the periphery of said head which is perpendicular to the plane of said blade.

It is preferred that the blade be made of so-called high-speed steel, and it is readily inserted and removed from the slot in the head for the purposes of renewal. In removing the blade, the clamp-screws 6 7 are removed, and a tapered pin, indicated at 42 in dotted lines in Fig. 4, is inserted into a hole 43 extending through said head at right angles to the slot and merging with the inner end of the slot, the tapered pin being arranged to be forced between the inner wall of said hole and the inner end of the blade 80 for forcing the blade outwardly.

A tool of the character described is thus provided in which the cutter-blade is braced by supporting metal to the maximum extent and large clearance provided for the chips produced in the cutting operation. The head may be provided with a shank 44 arranged to be inserted in a suitable chuck or other holding device of a machine for operating the same.

Having thus fully described my invention, what I claim as new and desire to secure by Letters Patent is:

1. A combined drill, center-reamer and countersink tool comprising in combination 95 a head provided with an end slot located in the axial plane of said head and extending lengthwise of said head from its end for forming a pair of wings, a cutter-blade having thereon a drilling section, a center-reaming section and a countersinking section received in said slot, and a clamp-screw received through said blade and clamping said wings toward said blade for clamping the blade in position, substantially as described.

2. A combined drill, center-reamer and countersink tool comprising in combination, a head provided with an end slot located in the axial plane of said head and extending lengthwise of said head from its end for forming a pair of wings, a cutter-blade having thereon an end drilling section, a middle center-reaming section and an inner counter-sinking section received in said slot, 115 the said middle center-reaming section having tapering edges, and a clamp-screw received through said blade and clamping said wings toward said blade for clamping said blade in position, the outer ends of said wings being provided with tapering portions contacting the sides of the middle section of said blade, substantially as described.

3. A combined drill, center-reamer and countersink tool comprising in combination 125 a head provided with an end slot located in the axial plane of said head and extending lengthwise of said head to a substantial extent from its end for forming a pair of wings, a flat cutter-blade having thereon a 130

middle tapered center-reaming section, a drilling section at the outer end of the latter, and a counter-sinking section at the inner end of said tapered center-reaming section, 5 said cutter-blade received in said slot, and a clamp-screw received through said blade and clamping said blade in position, the said cutter-blade being provided at the respective sides of its median line and at opposite sides of said blade with end cutting edges 15 and side cutting edges 16 at said drilling section, with end-cutting edges 18 at said counter-sinking section, and with inclined center-reaming cutting-edges 17 at 10 said center-reaming section which extend at acute angles with relation to each other and at obtuse angles with relation to said end-cutting edges 18 and side cutting-edges 16, the respective sides of said blade being 15

provided with clearance rake-grooves at the 20 respective edges of said blade which extend longitudinally of said cutting edges and follow the angles thereof, the said wings being provided with clearance recesses at said grooves, and the said wings being provided with outer parti-conical ends located at the respective sides of said tapered center-reaming section closely adjacent to the rear of the cutting edges of said blade, substantially as described. 25

In testimony whereof, I have signed my name hereto in the presence of two subscribing witnesses. 30

FREDERICK A. WAGNER.
